BOTTOM HOLE INTERMITTER

Charles M. O'Leary, Houston, Tex.

Application February 7, 1942, Serial No. 429,938

7 Claims. (Cl. 103—232)

The present invention relates generally to that type of pressure controlled and actuated devices, for intermittently causing upflow of liquid in a well, which are commonly known as bottom hole intermitters, and commonly used in oil wells wherein the formation pressure is insufficient to cause outflow of oil under well pressure.

Intermitters of the above type are usually employed in a manner to permit rise of oil under well pressure within production tubing to form a head or slug above the intermitter. During this rise of oil, known as the filling period or cycle, the intermitter is effective to prevent the entrance of casing pressure into the tubing, such pressure being provided in the casing from the surface. When the continued rise of oil under well pressure results in a head or slug of predetermined weight value, the intermitter acts to cut off further rise of oil, and at the same time admit casing pressure into the tubing for the purpose of blowing to the surface, during the second, or production cycle, the head of oil previously accumulated during the preceding filling cycle. Many practical considerations are involved in the successful use of a bottom hole intermitter, however, and among them may be mentioned the following.

Since intermitters of the above character utilize casing pressure provided from the surface and are for wells having a formation pressure less than that required to continuously flow the same, they are commonly employed with means packing off the casing pressure from the producing formation for preventing back pressure on the latter. It is very important not to prevent, but rather to facilitate, rise of well liquid during the filling cycle.

Furthermore, such intermitters must operate with equal facility in wells of varying pressures, in many of which the formation pressure is very low and the filling cycles are slow, and in many of which the formation pressure is such that it quickly builds up during each production cycle sufficient to cause sudden and rapid rise of well liquid during the initial portion, at least, of each filling cycle. This latter condition gives rise to what is commonly known as a "false filling head" and frequently results in fluttering of the intermitter valves and inefficient operation.

It is the primary object of the present invention to provide an intermitter of the type set forth, including a casing pressure flow valve, and a well liquid flow valve, each of which is effectively held closed while the other is open, which valves are so related that their movements will

be positive and unfailing in the presence of varying well or formation pressures.

A further object of the invention is the provision of an intermitter in which the valves will be proof against fluttering or uncertain action, and in which they will be guided by means protected at all times against flowing pressure as well as flowing liquid, so that all danger of sticking will be eliminated and a lasting, durable and trouble free life will be assured.

With the above general statement and objects in mind, further objects, as well as the resulting advantages of the present invention may be better understood and more thoroughly appreciated 15 from the following description in detail thereof, and by reference to the accompanying drawing, illustrating a practical example of the invention, and forming a part of this specification. In this drawing,

20 Figure 1 is a vertical sectional view illustrating in a more or less diagrammatic manner, the installation of the bottom hole intermitter in a well.

Figure 2 is an enlarged detail vertical sectional view through the intermitter, and,

25 Figures 3 and 4 are detail transverse sectional views taken respectively on lines 3—3 and 4—4 of Figure 2.

Referring now particularly to Figure 1, there is shown an example of installation of the invention 30 in which flow or eduction tubing 10 is illustrated within a well casing 11, carrying at its lower end a cylindrical housing 12, forming therein a pressure chamber 13. This housing 12 is shown as surrounded by packing 14 within the well casing 11, which prevents pressure, fed into the latter from the surface, from undesirable influence upon the producing formation below the well casing.

The housing 12 is also shown with a pressure 40 inlet 15 below its top 16 and above the packing 14, which places the chamber 13 in communication with the interior of the well casing 11. Within this chamber is shown tubing 17 depending from, and opening upwardly through, the top 16 of the housing and thus in communication with the lower end of the eduction tubing 10.

The lower end of tubing 17 is connected to, and opens within, the upper section 18 of a cylindrical casing which houses the intermitter valve, and 50 whose lower section 19 depends through the lower closed end 20 of housing 12, and is open at its lower end into the producing zone of the well below the packer 14.

Thus oil from the producing formation may 55 rise within the lower end of the lower section 19

of the intermitter casing, and the upper end of the upper section is in communication with the eduction tubing 10. In addition, the upper section 18 has, intermediate its ends, casing pressure flow openings 21 by which it receives casing pressure from within the pressure chamber 13.

Referring to Figure 2, the upper section 18 of the intermitter casing is shown with an internal valve seat ring 22 above the pressure flow openings 21. The lower section 19 is shown with a standing valve 23 in its lower end, which opens to the rise of well liquid. These two sections 18 and 19 are connected at their adjacent ends by a valve or partition coupling 24 which separates the gas or pressure chamber 25, within section 18, from the oil or well liquid chamber 26, within section 19, these chambers being completely isolated from each other.

The valve member within the intermitter casing, consists of an elongated tubular central stem 27 which is shiftable lengthwise in an axial bore 28 of the coupling 24. On the upper end of stem 27 is a valve head 29 adapted to seat, in the upper position of the valve member, against valve seat ring 22. On the lower end of said stem is a valve head 30 adapted to seat, in the lower position of the valve member, on a valve pin 31 which may be supported axially of the lower portion of the liquid chamber 26, on the cage 32 of the standing valve 23.

The valve stem 27 forms therein a liquid flow passage, open at its lower end into the liquid chamber 26, through liquid valve 30, only when the latter is unseated as it is when the valve member is in its upper position. At its upper end, the said passage is open, through pressure flow valve 29, at all times into the tubing 17, and thus in constant communication with the eduction tubing 10.

The valve stem 27 also slides through, and is guided by, a guide sleeve 33 rising from the coupling 24, the upper end of said sleeve entering a counterbore in the lower face of the pressure flow valve 29. A bellows 34 surrounds sleeve 33, with its upper end sealed in connection with pressure flow valve 29, and its lower end similarly sealed in connection with the upper surface of coupling 24.

Around the lower portion of the stem 27 of the valve member, a second bellows 35, of substantially less effective area than the bellows 34, is disposed with its upper end in sealed connection with the lower surface of coupling 24, and its lower end in similarly sealed connection with the liquid flow valve 30. Externally of the latter bellows 35, a surrounding coil spring 36 is disposed under compression between coupling 24 and the liquid flow valve 30, tending to press the valve member downwardly at all times from its upper liquid rising position shown in Figure 2, to its lower pressure flowing position wherein the rise of liquid is cut off.

The coupling 24 is shown with gas or pressure ports 37 in its wall in open communication with the pressure chamber 13, from which ports feed channels 38 extend upwardly and open at their upper ends into the lower end of bellows 34, so as to maintain within both bellows 34 and 35, the existing casing pressure at all times. It is to be noted, however, this arrangement forms no part of the pressure flow passage or line in operation.

It will also be noted that the effective area of bellows 34, while greater than that of bellows 35, is somewhat less than the effective area of the seat 22 of the pressure flow valve 29. On the

other hand, the effective area of bellows 35 is preferably less, and certainly not greater, than the effective seating area of the liquid flow valve 30.

5 Thus, with the parts in the position of Figure 2 during each filling cycle, oil or well liquid rises under formation pressure through the standing valve 23, into liquid chamber 26 and from this chamber through the valve stem 27 and tubing 10, 17, into the eduction tubing 10. At this time casing pressure is cut off from the tubing 10, by reason of the fact that pressure flow valve 29 is held on its seat 22 by pressure upwardly thereagainst externally and internally of bellows 34. 15 Such pressure overcomes the pressure within the smaller lower bellows 35 and that exerted by the spring 36, and is effective to tightly hold the pressure flow valve in closed position. Since the effective area of bellows 34 is somewhat less than the effective area of valve seat 22 it is apparent that when valve 29 is seated the pressure in chamber 25 becomes effective to create an upward closing or seating force on valve 29 which holds it more tightly against its seat. When valve 29 25 is open however the pressure in chamber 25 no longer tends to create an upward closing force.

When, during the filling cycle, a liquid head or slug builds up in the eduction tubing 10, and reaches a weight value on the upper effective area of valve 29, sufficient to overcome the previously preponderant casing pressure tending to hold the valve closed as above, it will, with the help of the spring 36 and the pressure within the smaller, lower bellows 35 against the liquid valve 30, force the valve member downwardly, thus unseating the pressure flow valve 29 and seating the liquid flow valve 30.

With the valve member in lower position, pressure flow valve 29 is open, permitting the flow of casing pressure into the tubing 10 through the restricted openings 21, and thus, with valve 30 closed and cutting off further rise of well liquid, the head or slug of oil, previously accumulated, will be caused to upflow in the tubing to discharge. During this period, known as the production cycle, after the slug reaches the surface and discharges, there is a pressure drop in the tubing above the intermitter and also in chamber 25, due to the restricted flow of pressure through openings 21. When this drop occurs, the constant pressure within bellows 34, acting against the preponderantly greater lower area of valve 29, overcomes pressure in the lower, smaller bellows 35 acting against the liquid valve 30, plus the pressure of spring 36, to thus again shift the valve member upwardly to seat the pressure flow valve 29 and unseat the liquid flow valve 30, for the next filling cycle.

Should considerable pressure build up below 60 the intermitter and within liquid chamber 26 during the blow down or production cycle, it will act during such cycle merely as an additional means maintaining the liquid valve 30 in seated position, since the effective area of the lower bellows 35 is no greater, and is preferably less, than the effective seating area of said valve. When the liquid flow valve 30 is unseated at the start of a filling cycle such liquid pressure as above, cannot have the effect of closing or seating the valve, since the latter will tend to be held upwardly by the up-rush of the liquid passing through the tubular valve member.

It is apparent that by varying the effective tension of the spring 36, it is possible to increase 75 and decrease the height or head of oil formed in

the tubing 10 during each filling cycle. This same result may, of course, be obtained by the regulation of the casing pressure which, in operation flows only through pressure chamber 25 and past valve 29. Since the bellows feed channels 38 form no part of the pressure flow passage, there is no tendency toward carrying foreign matter into the bellows and the guiding means for the valve member. Thus the bellows act to protect the guiding portions of the valve member at all times against foreign matter in the gas as well as the oil.

Having thus fully disclosed the present invention, what is claimed is:

1. In a bottom hole intermitter, a casing having therein a pressure fluid flow passage, a valve member movable in the casing to close said passage in one position thereof and open said passage in another position thereof for the upflow of pressure fluid, said valve member having a liquid flow passage therein for the upflow of liquid entering the lower portion of the casing, means positioned to cooperate with said valve member for opening its said liquid flow passage in its first mentioned position and closing said liquid flow passage in its last mentioned position, said valve member being exposed externally thereof within the pressure fluid flow passage, means forming a pressure chamber internally of said valve member, and means for supplying pressure fluid to said internal chamber of the valve member independent of, and isolated from, the pressure fluid and liquid flow passages.

2. In a bottom hole intermitter, a casing having therein a pressure fluid flow passage, a valve member movable in the casing to close said passage in one position thereof and open said passage in another position thereof for the upflow of pressure fluid, said valve member being of unitary nature and having a liquid flow passage therein for the upflow of liquid entering the lower portion of the casing, means positioned to cooperate with said valve member for opening its said liquid flow passage in its said first mentioned position and closing said liquid flow passage in its last mentioned position, said valve member being exposed externally thereof to the influence of pressure fluid in the pressure flow passage, means forming a pressure chamber internally of said valve member, and means for supplying pressure fluid to said internal chamber of the valve member independent of, and isolated from, the pressure fluid and liquid flow passages.

3. A bottom hole intermitter, including a casing having therein a pressure chamber and a liquid chamber, a valve member, means controlled by said valve member and movable in said chambers to alternately open the liquid chamber for upflow of liquid therefrom and close the pressure chamber in one position thereof and to open the pressure chamber for upflow of pressure fluid therefrom and close the liquid chamber in the other position thereof, said valve member being exposed to the influence of pressures in said chambers, means forming a pressure chamber within the valve member isolated from the first mentioned chambers, and means for constantly supplying valve controlling pressure within the said pressure chamber of the valve member, independent of the first mentioned pressure chambers.

4. In a bottom hole intermitter, a casing having a pressure chamber provided with a restricted pressure inlet and a pressure flow passage above

10 the inlet, and also having a liquid chamber provided with a liquid inlet, a unitary valve member shiftable in said casing and having a liquid flow channel, means controlled by said valve member to alternately open the liquid flow channel and close the pressure flow passage in one position thereof, for the upflow of liquid and to open the pressure flow passage and close the liquid flow channel in the other position thereof, for the upflow of pressure fluid, spring means tending to force said member to pressure flow position, and means isolated from said liquid and pressure flow passages for admitting pressure into said valve member tending to force the said member to liquid flow position.

5. In a bottom hole intermitter, a casing having a pressure chamber provided with a restricted pressure inlet and a pressure flow passage above said inlet, and also having a liquid chamber provided with a liquid inlet, a unitary valve member shiftable in said casing and having a liquid flow passage, means controlled by said valve member to alternately open the liquid flow channel and close the pressure flow passage in one position thereof, for the upflow of liquid and to open the pressure flow passage and close the liquid flow channel in the other position thereof, for the upflow of pressure fluid, said member being exposed externally thereof to pressure in the pressure chamber, means in sealed connection with said valve member forming an internal pressure chamber within the member, and means for admitting pressure to said internal pressure chamber to shift the valve member to liquid flow position, independent of, and isolated from, the said pressure and liquid chambers and flow passages of the casing.

6. A bottom hole intermitter, including a casing having an upper outlet and a lower inlet, 40 and having an intermediate partition dividing the same into an upper pressure chamber and a lower liquid chamber, valve seats in said chambers, a valve member shiftable axially through said partition, having upper and lower valve heads respectively engageable with said seats in the upper and lower positions of said valve member, said valve member having a liquid passage for the upflow of liquid from the liquid chamber when the valve member is in upper position, 50 and said valve heads being exposed to the influence of pressure in said chambers and relatively positioned to alternately open upflow of liquid and close upflow of pressure in the upper position of the valve member, and to open upflow of pressure fluid and close upflow of liquid in the lower portion of the valve member, flexible means in sealed connection with the valve heads and the casing partition and forming an internal pressure chamber within the valve member, and 60 means in said partition for admitting pressure into said internal chamber independent of, and isolated from, the pressure and liquid chambers of the casing.

7. A bottom hole intermitter, including a casing having an upper outlet and a lower inlet, and having an intermediate partition dividing the same into an upper pressure chamber and a lower liquid chamber, valve seats in said chambers, a valve member including a hollow stem 70 shiftable axially through the said partition, forming a liquid flow passage, and also having upper and lower valve heads arranged respectively to move off of the seat of the liquid chamber and onto the seat of the pressure chamber in one position of the valve member for the up-

flow of liquid, and to move onto the seat of the liquid chamber and off of the seat of the pressure chamber in the other position of the valve member for the upflow of pressure fluid, the valve heads being within, and exposed to the pressure in, said pressure and liquid chambers, bellows in sealed connection with the valve heads and said casing partition and forming a pressure

chamber within the valve member around its stem, said partition having externally opening ports and channels from said ports opening into the said internal pressure chamber of the valve member, for supplying pressure thereto independent of, and isolated from the pressure chambers of the casing.

CHARLES M. O'LEARY,
